H. Colomb,
By Marcus Clark
Atty*

UNITED STATES PATENT OFFICE.

HENRI COLOMB, OF TAVANNES, SWITZERLAND.

TIMEPIECE.

Application filed January 6, 1922. Serial No. 527,477.

To all whom it may concern:

Be it known that I, HENRI COLOMB, a citizen of Switzerland, residing at Tavannes, Switzerland, have invented certain new and useful Improvements in Timepieces, of which the following is a specification.

In order to change the main-spring of a time piece, it is necessary to remove the barrel; it is therefore of great importance, especially for the repairer, that the latter may easily and rapidly be removed.

In time-pieces called "cock-pieces", that is to say, pieces in which each wheel and particularly the barrel turn in an independent cock, disassembling is comparatively easy. In pieces called "3/4 plate pieces", however, in which the same cock covers the barrel, the centre wheel, the third wheel, the fourth wheel and the escapement wheel, the operation is more difficult. The removal of the barrel necessitates almost the complete disassembling of the movement; this, of course, complicates the re-assembling and increases the risks of breaking inherent to this operation.

The spring motor for time pieces according to the present invention is of such a construction that the core of the barrel may be removed without necessitating the removal of the cock or of the plate in which the barrel is rotatably mounted. In order to change the broken spring it is then possible to remove the barrel by radially moving it between the plate and the cock, and afterwards to replace the barrel and core in a manner corresponding to that of removal.

The annexed drawings show a constructional example of a spring motor according to the invention.

Fig. 1 is a section of this form of execution taken through the axis of the barrel;

Fig. 2 is a plan view according to line II-II of Fig. 1.

The motor shown comprises a barrel *a* without cover, turning between a cock *b* and a plate *c*. The cock *b* is provided with a removable bearing *d* adjustably mounted in a suitable orifice provided in the cock. This bearing *d* is held in operative position by a screw *e* and its diameter is greater than that of the core *f*, so that the latter may be axially inserted or removed through the aperture in which the bearing *d* is adapted to be housed when the said aperture is free.

The barrel can thus be unlocked, and may then be removed sideways between the plate and the cock.

The shaft *g* is provided with a squared portion *h* on which is adjusted the ratchet wheel *i* which is a part of a clickwork whose click and spring are shown in Fig. 2. The main-spring is wound up by means of said ratchet wheel *i*. Preferably, the above mentioned click is pressed by a spring against the said ratchet wheel. As soon as the barrel shaft has been removed from the piece, the ratchet wheel *i* tends to move radially, under the pressure of the click, that is to say to displace, relative to the pivoting hole *k*, the axis of the orifice by which it is fitted on the squared portion *h*. This motion is limited by three pins *l* (only two of which are illustrated) which may be termed abutment members. These pins are disposed in a circle which exceeds by some hundredths of millimeter the outer circle of the ratchet *i*, and prevent radial displacement of the barrel axis to an extent sufficient to prevent the square *h* from being introduced into the corresponding hole so that when, after having changed the spring and replaced the barrel, the barrel shaft is introduced into the latter through the orifice of the bearing *d*, the ratchet *i* is so positioned as to be capable of receiving the square *h*.

I claim:

1. In a time piece, a plate member, a cock member spaced from said plate member, one of said members being provided with an aperture, a removable bearing arranged in said aperture, an axle turning in said bearing, a spring core mounted on said axle, the diameter of said aperture being at least equal to that of the core so that the latter may be removed without necessitating disassembling of the movement, a barrel and ratchet mechanism including a ratchet wheel arranged between the plate member and cock member, and means cooperating with the ratchet mechanism for preventing said ratchet wheel from radial displacement relative to the axis of said axle.

2. In a time piece, a plate member, a cock member spaced from said plate member, one of said members being provided with an aperture, a removable bearing arranged in said aperture, an axle turning in said bear-

ing, a spring core mounted on said axle, the diameter of said aperture being at least equal to that of the core so that the latter may be removed without necessitating dis-
5 assembling of the movement, a ratchet wheel mounted on said axle, a spring pressed pawl cooperating with said ratchet wheel, and

abutment pins projecting from said plate member and cooperating with said ratchet wheel for preventing undue radial displacement of the latter when said axle is removed.

10 In testimony whereof I affix my signature.

HENRI COLOMB.
